United States Patent Office

Des. 200,842
Patented Apr. 13, 1965

200,842

BEER KEG

Carlos M. Baranano, 17 Lowry Drive, Wilmington, Del.

Filed May 11, 1964, Ser. No. 79,912

Term of patent 14 years

(Cl. D2—3)

FIG. 1

FIG. 2

FIG. 4

FIG. 3

FIGURE 1 is a perspective view of a beer keg, showing my new design.

FIGURE 2 is a side elevational view thereof.

FIGURE 3 is a top view thereof.

FIGURE 4 is a bottom view thereof.

The dominant features of my design reside in the portions shown in full lines.

I claim:

The ornamental design for a beer keg, as shown and described.

References Cited by the Examiner

UNITED STATES PATENTS

D. 92,295 5/34 Garlent ----- D58—3
D. 112,636 12/38 Goll et al. ----- D58—3
3,104,758 9/64 Allen et al.

WALLACE R. BURKE, Acting Primary Examiner.